(57) **CLAIM**

The ornamental design for an injection device with pull off strip, as shown and described.

DESCRIPTION

FIG. 1 is a perspective view of an injection device with a pull strip, showing our new design;

FIG. 2 is a perspective view thereof, with the pull strip removed;

FIG. 3 is another perspective view of FIG. 1, rotated 90 degrees;

FIG. 4 is another perspective view of FIG. 2, rotated 90 degrees;

FIG. 5 is a right end elevational view thereof; and,

FIG. 6 is a left end elevational view thereof.
